United States Patent

Des. 241,949
Patented Oct. 19, 1976

241,949

DIRECT STATION SELECTION CONSOLE

Paul S. Marchese, New York, N.Y., assignor to
TIE/Communications, Inc., Stamford, Conn.

Filed Mar. 4, 1974, Ser. No. 447,915

Term of patent 14 years

Int. Cl. D14—03

U.S. Cl. D26—14 A

Fig. 1.

Fig. 2.

Fig. 3.

FIG. 1 is a top plan view of a direct station selection console showing my new design;

FIG. 2 is a front elevational view thereof;

FIG. 3 is a back elevational view thereof;

FIG. 4 is a right side elevational view thereof;

FIG. 5 is a left side elevational view thereof; and

FIG. 6 is a front perspective view thereof.

I claim:

The ornamental design for a direct station selection console, as shown and described.
